UNITED STATES PATENT OFFICE.

CHARLES T. WESTLAKE, OF ST. LOUIS, MISSOURI.

CAR-BOLSTER.

SPECIFICATION forming part of Letters Patent No. 514,797, dated February 13, 1894.

Application filed September 26, 1893. Serial No. 486,567. (No model.)

To all whom it may concern:

Be it known that I, CHARLES T. WESTLAKE, of St. Louis, State of Missouri, have invented certain new and useful Improvements in Car-Bolsters, of which the following is a full, clear, and exact description, reference being had to the accompanying drawings, forming a part hereof.

My invention relates to an improved car-bolster, and consists in the novel arrangement, combination and construction of parts, will be more fully hereinafter described and designated in the claims.

In the drawings: Figure 1 is a top plan view of my improved bolster, a portion being broken away. Fig. 2 is a bottom plan view of the same. Fig. 3 is a side elevation of the same. Fig. 4 is a longitudinal section taken on the line 4—4 of Fig. 1. Fig. 5 is an end elevation. Fig. 6 is a vertical cross-section taken on the line 6—6 of Fig. 3. Fig. 7 is a like section taken on the line 7—7 in Fig. 3.

My improved bolster is especially adapted to be used on trucks of that class in which the bolster is supported at its ends upon springs located in a truck-frame of the usual construction.

1 indicates a car bolster, which is constructed with an I-beam which is provided with a central-bearing 2 and end-bearings 3. Said I-beam is constructed with a vertical longitudinal web 4. Formed on the lower edge of the web 4 is a horizontal plate 5 which is straight in side elevation and in plan view is wider at its ends than at its center. (See Fig. 2 for illustration.)

6 indicates the upper plate of the I-beam, which slopes downward from the central bearing 2 a suitable distance and its ends project 40 downward and are connected to the plate 5. They also branch outward from the web 4 around the outward ends of the bottom-plate 5, terminating adjacent the center of said ends. I will designate these branches by the 45 numeral 7. The ends of the bottom-plate 5 are constructed to form spring-plates 6', and the web 4 extends outward onto said plates and terminates thereon. (See Figs. 1 and 3 for illustration.) The upper sloping plate 6 50 of the I-beam is made of less cross-sectional area and is narrower intermediate of its ends and the central bearing 2. (See Fig. 1

for illustration.) The purpose of this being narrower is to lighten the bolster, and the sloping plate is constructed to stand compression strain only; therefore it does not need to be so wide or of as great cross-sectional area as the bottom-plate 5, as the bottom-plate 5 is constructed to stand the tensile strain. Around the spring-plates 6' vertical 60 projections 8 are formed thereon for column bearings and increased area of section to resist sheering strain at this point. By the plates 6 of the I-beam sloping downward from the central bearing 2 and by the sloping of 65 this plate toward both ends, it forms a compression truss which continues downward and connects to the bottom-plate, as hereinbefore stated, through the branches 7.

The central bearing 2 of the bolster is constructed with a vertical bore 9 so it can be readily connected to a car in the ordinary manner.

Formed on the bottom-plate 5 around the bore 9 is a swollen portion 10 to overcome 75 loss of area by said bore passing through the plate, thereby obtaining necessary area of said plate.

Vertical webs 11 are cast integral with the web 4 and the upper and lower plates intermediate of the ends of the bolster. These webs are to strengthen the bolster when a twisting or cross-strain comes on the bolster.

When a bolster is applied to the truck and weight is applied on the central bearing in the 80 usual way, the I-beam will act as a truss, and the top-plate sloping as hereinbefore described and the bottom plate being horizontal, the top plate will form a compression-truss while the bottom-plate will stand a tensile strain, thus forming a very complete truss in the car bolster. As shown by dotted lines in 85 Figs. 3 and 4. The web 4 can be cored between the upper and lower plates, thus reducing the weight of the bolster, if desired.

I am aware that car bolsters are made integral both of pressed and cast steel. The weight to be carried is so great and the space for bolster is so limited, that it has been found very difficult to prevent fracture in 90 either pressed or cast steel when the supports are presented edgewise to the strain. I overcome this difficulty by the truss formation, as shown in drawings, which gives the en-

tire strength of the upper plate for compression and the lower plate for tensile strain; in other words I convert the weight to be carried to a complete push and pull strain, thus 5 avoiding the cross or tearing strain that is so harmful in other plans of metal car bolsters.

What I claim is—

- 10 1. A cast or malleable car bolster, provided with suitable bearings, and in the form of an **I** beam in cross-section, the lower edge of said beam being straight while the upper edge slopes from the center toward each end, substantially as set forth.
- 15 2. A cast steel or malleable car bolster formed of an **I**-beam in cross-section, the upper plate of said **I**-beam sloping from its center while the lower plate is straight, and the upper plate being less in cross sectional area than the lower one, substantially as set forth.
- 20 3. An integral cast steel or malleable car

bolster **I**-shaped in cross section, the upper plate of less cross-sectional area than the lower plate thereof, and provided with spring plates and a center bearing, substantially as set forth.

25

4. A cast steel or malleable car bolster **I**-shaped in cross-section, having an upper plate of less cross sectional area than the lower plate thereof, a center bearing formed in said bolster, and said lower plate having a swelled portion adjacent said center bearing to strengthen said plate thereat, substantially as herein specified.

30

In testimony whereof I affix my signature in presence of two witnesses.

CHARLES T. WESTLAKE.

Correction in Letters Patent No. 514,797.

It is hereby certified that in Letters Patent No. 514,797, granted February 13, 1894, upon the application of Charles T. Westlake, of St. Louis, Missouri, for an improvement in "Car-Bolsters," an error appears in the printed specification requiring correction, as follows: In line 12, page 2, the word "cutter" should read *center*; and that the said Letters Patent should be read with this correction therein that the same may conform to the record of the case in the Patent Office.

Signed, countersigned, and sealed this 23d day of April, A. D. 1895.

[SEAL.]

JNO. M. REYNOLDS,
Assistant Secretary of the Interior.

Countersigned:

JOHN S. SEYMOUR,
Commissioner of Patents.
